HACKAMORE BIT

Robert W. Askin, Ismay, Mont.

Application May 2, 1945, Serial No. 591,613

1 Claim. (Cl. 54—7)

1

The present invention relates to a new and useful improvement in hackamore bits for use in driving horses and designed to effectively control the movements of the horse.

An important object of the present invention is to provide means for exerting pressure on a nose strap and jaw strap simultaneously by a pulling force exerted on the reins.

More specifically, the invention embodies the provision of interengaging gear segments operated by a pulling force exerted on the reins to increase the pressure on the nose and jaw straps.

A further object of invention is to provide a device of this character of simple and practical construction, which is strong and durable, neat and attractive in appearance, efficient and reliable in use, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a perspective view.

Figure 2 is a side elevational view.

Figure 3 is a rear elevational view.

Figure 4 is a vertical sectional view taken substantially on a line 4—4 of Figure 2.

Figure 5 is a perspective view of one of the flanged retaining nuts and

Figure 6 is a side elevational view showing the device in use.

Referring now to the drawings in detail wherein for the purpose of illustration I have disclosed a preferred embodiment of invention. The numerals 5 and 6 designate a pair of rein levers which are curved rearwardly at their lower ends and provided with eyes 7 by means of which the reins 8 may be attached thereto.

The upper portion of the levers are connected by a mouthpiece 9 in the form of a smooth bar adapted for insertion in the mouth of a horse, each end of the mouth being formed with an inner threaded portion 10, an outer threaded portion 11, and an intermediate smooth portion 12, all of successively reduced diameter as indicated in Figure 4 of the drawings.

A cheek plate 13 is threaded at its lower portion on the inner threaded section 10 of the mouthpiece 9 and extends upwardly therefrom, the inner side of the cheek plate abutting the shoulder 14 formed at the inner end of the threaded portion 10.

A flanged nut 15 is threaded on the outer

2

threaded portion 11 outwardly of the lever, the nut 15 being formed with an inwardly projecting annular collar 16 forming a bearing for the smooth portion 12 of the mouth piece and on which the lever is mounted for pivotal movement. The inner end of the collar 16 abuts the outer end of the threaded portion 10 to prevent binding of the lever on the collar 16.

The cheek plate 13 is formed with an opening 17 adjacent its upper portion on the inner side of which a screw 18 is countersunk, the screw having a flanged nut 19 threaded on its outer end and also provided with an inwardly projecting collar 20 on which a gear segment 21 is rotatably mounted, the gear segment 21 being engaged with a gear segment 22 formed on the upper end of the adjacent lever.

Each of the levers 5 and 6 are operatively engaged with one of the gear segments 21 pivotally mounted on a cheek plate 13 at the opposite sides of the head of the horse.

An extension 23 projects rearwardly from the upper portions of each of the levers and is provided with an opening 24 for attaching a jaw strap 25 thereto for extending transversely under the jaw 26 of the horse.

An extension 27 projects forwardly from the gear segment 21 and is formed with a slot 28 for attaching a nose strap 29 thereto adapted for extending transversely over the nose 30 of the horse.

The upper end of the cheek plate 13 is also formed with a slot 31 for attaching a head strap 32 thereto.

Accordingly, in the operation of the device and with the levers 5 and 6 positioned at opposite sides of the head of the horse and each operatively connected at their upper ends with a gear segment 21 pivoted on a cheek plate 13 and with a jaw strap 25, nose strap 29 and head strap 32 attached in the manner as indicated in Figure 6 of the drawings a pulling force exerted on the reins 8 will cause a rotation of the levers 5 and 6 on the collars 16 carried at the smooth portion 12 of the mouth piece 9 whereby to rotate the gear segments 21 and cause the nose strap 29 to be tightened over the nose of the horse as well as to cause the jaw strap 25 to be tightened under the jaw of the horse and thus serve to bring the horse under control when desired.

In view of the foregoing description taken in conjunction with the accompanying drawings it is believed that a clear understanding of the construction, operation and advantages of the device will be quite apparent to those skilled in the art.

A more detailed description is accordingly deemed unnecessary.

It is to be understood, however, that even though there is herein shown and described a preferred embodiment of the invention the same is susceptible to certain changes fully comprehended by the spirit of the invention as herein described and claimed.

I claim:

A hackamore bit comprising a pair of cheek plates, a mouth bar rigidly connecting the cheek plates, head straps extending upwardly from the cheek plates, a pair of levers pivoted on the mouth bar and adapted for attaching a pair of reins

thereto, extensions projecting rearwardly from the levers, a jaw strap connected to said extensions, said levers having gear segments formed at their upper edges, gear segments rotatably mounted on the cheek plates and operatively engaged with the gear segments first mentioned, extensions projecting forwardly of the gear segments, and a nose strap connected to said last named extensions, said jaw and nose straps being compressed respectively under the jaw and over the nose of an animal upon a pulling force exerted on the reins.

ROBERT W. ASKIN.
